CLOTHES WASHING MACHINE

Henry Dreyfuss, South Pasadena, Calif., and Robert H. Hose, Mountainside, N.J., assignors to The Hoover Company, North Canton, Ohio, a corporation of Ohio

Filed Nov. 3, 1960, Ser. No. 62,719

Claims priority, application Great Britain May 12, 1960

Term of patent 14 years

(Cl. D49—1)

Fig. 1

Fig. 2

The dominant features of my design reside in the portions shown in full lines on the drawings.

We claim:

The ornamental design for a clothes washing machine, substantially as shown and described.
